UNITED STATES PATENT OFFICE.

JOSEPH E. PIGEON, OF HOLLYWOOD, CALIFORNIA.

AERONAUTICS.

Application filed July 12, 1927. Serial No. 205,211.

This invention relates to improvements in aeronautics having for an object to provide a dirigible airship whose flight efficiency is derived from a novel combination and construction of lighter than air and plane sustaining bodies, while propeller and steering means are supplied, that the vehicle may be driven upon or through a properly navigated course.

10 It is also amongst the principal desiderata of the invention to provide an airship of the character mentioned wherein the body construction is such that the craft may be advantageously used for commercial purposes, space being provided therein for the reception or storage of both freight and passenger cargos, while other space is available for the storing of fuel for the airship motors, this reservoir receiving space being so disposed that the added weight of the fuel will give an extremely low center of gravity to the airship and hence, materially stabilize the flight efficiency thereof.

15 Amongst other aims and objects of the invention there may be noted, the provision of an airship having propeller means for driving the same through a navigated course and also, at will of a navigator, to accelerate or positively effect ascension of the ship as in the process of "take off" thereof, when heavily laden.

20 Other objects of the invention will be in part obvious and in part pointed out herein-after.

25 In order that the invention and its mode of operation may be readily understood by those skilled in the art, I have in the accompanying illustrative drawings and in the detailed following description based thereupon, set out one possible embodiment of the invention.

In these drawings:

Figure 1 is a side elevation of the improved air ship,

45 Figure 2 is an enlarged vertical transverse section therethrough taken on the line 2—2 of Figure 1,

Figure 3 is a horizontal and longitudinal section through the improved air ship,

50 Figure 4 is a vertical fragmentary longitudinal section through the lower portion of the ship showing the manner in which the fuel reservoirs thereof are disposed with respect to the landing gear and the arrangement of the passenger receiving compartments, and

55 Figure 5 is a fragmentary horizontal and longitudinal section through the ship showing the arrangement and disposition of one of the plane sustaining bodies employed in combination with the lighter than air sustaining bodies.

Having more particular reference to the drawings, in connection with which like characters of reference will designate corresponding parts throughout, the improved air ship may be stated to comprise a super structure generally indicated herein by the numeral 1, portions of said super structure being arranged to constitute tubular bodies 2 and 3 70 adapted to be lined and covered with a gas impervious fabric material 4 whereby with the pumping of gas into the tubular enclosures so constituted, lighter than air supporting or sustaining bodies will be afforded the ship. 75 Other portions of the super structure 1 and particularly, those portions of the same outwardly and laterally of the tubular bodies 2 and 3 are formed into auxiliary tubular bodies of substantially triangular cross sectional shape, designated by the numeral 5, are provided, these particular bodies being lined with a gaseous impervious fabric or material designated by the numeral 6, whereby with inflation of the same, auxiliary lighter than air sustaining bodies will be afforded. 80 The whole of the super structure together with the lighter than air sustaining bodies 2, 3 and 5 is adapted to be covered by a fabric or other material indicated by the numeral 7, 85 90 this serving as a protecting means therefor against the elements and likewise, as a friction minimizing means.

95 Supported upon portions of the super structure 1 and arranged below the lighter than air sustaining bodies 2, 3 and 6 are outwardly and laterally disposed plane sustaining bodies 8, these bodies, as shown in the Figures 1 and 5, being extended throughout the length of said super structure 1 and serving as an additional light sustaining means for the air ship.

100 A body or hull (fuselage) generally indicated by the numeral 9, is adapted to be securely joined or connected to the super structure 1 and depends therefrom in the manner as is shown in the Figure 2; this body 9 being divided by horizontal partitions 10 and 11 into upper and lower decks, the upper deck having a plurality of vertical longitudinally and transversely disposed partitions generally identified by the numeral 12 arranged

thereupon whereby to provide freight and passenger storage and receiving spaces or compartments designated, respectively, by the numerals 13 and 14, doors or other suitable ways of ingress and egress being provided each partition 12 for obvious purposes. Other compartments 15, may be formed or provided for upon the upper deck and in these compartments, accommodations for the air ship crew and maintenance force thereof may be supplied.

That the air ship may be driven and steered through a navigated course, compartments or rooms generally indicated by the numerals 16 and 17 are provided the body or hull portion 9, the compartments 16 serving to receive the engines or motors of the air ship, while the compartment 17 is arranged adjacent the bow or forward end of the air ship 20 and preferably in a plane corresponding to or slightly above that of the super structure 1, in order that proper observations may be made by the ship navigator or pilot.

Series of longitudinally disposed and forwardly directed rotatable propellers designated by the numeral 18 are suitably supported in positions laterally and outwardly of the opposite side of the air ship body 9 and each of these propellers are connected by gearing generally indicated at 19 to motors or engines 20 mounted within the aforesaid compartments 16. Also, other propellers 21 are rotatably mounted upon the front or bow portion of the body 9 and as will be understood, 35 assist in the driving or propulsion of the air ship through its course.

Within the lower deck of the body 9, compartments 22 are provided and in these compartments, fuel storage tanks or reservoirs 23 are immovably mounted or secured through the medium of brackets or straps indicated at 24; suitable conduit connections being effected as between these fuel reservoirs 23 and the various motors 20 that fuel may be delivered thereto for consumption. In this connection, it is to be noted that the fuel tanks or reservoirs 23 are arranged within the lowermost portion of the body 9, that is, in the lower deck and consequently thereupon, the 45 added weight of these tanks, especially when filled with fuel, will serve to materially lower the center of gravity of the air ship and hence, to greater materialize its flight efficiency.

55 Wheeled or other approved and prevalent type of landing gear designated by the numeral 25 is secured to the bottom or lower portion of the air ship body 9 and this landing gear is preferably equipped with suitable springs or other types of shock absorbing means or suspension devices indicated at 26, whereby to permit of an efficient landing of the craft upon terrain, as well as to permit of smooth or even taxiing of the same during the process of a "take off". Thus, it will

be understood that damaging or abnormal stressing of parts or elements of the air ship, especially during landing of the same will be avoided, particularly, the avoidance of "pan caking" of the ship when landing upon terrain under the sustaining influence of these lateral sustaining planes 8. 70

With a view toward providing the air ship with means for accelerating or positively effecting ascension thereof, as when the ship "takes off" with a heavy cargo, I provide a plurality or series of equi-spaced longitudinally disposed tubes generally designated by the numeral 27, these tubes being disposed throughout the combined depths of the super structure 1 and the air ship body or hull 9, as is clearly shown in the Figure 2; the upper and lower ends of the tubes being open and having enlarged collar extensions 28 secured to the upper extremities thereof in which normally horizontally positioned rotatable propellers 29 are mounted upon driving shafts 30 arranged within and disposed longitudinally of portions of the lengths of their respective tubes 90 27. These driven shafts 30, as will be understood, are connected by suitable gearing (not shown herein) to the motor or engines 20 of the air ship and by proper controls (also not shown) may be caused to rotate at such speeds as will be productive of a maximum lifting efficiency of the air ship. Therefore, it is to be understood that when an air ship constructed in accordance with my invention is so heavily laden as to possibly prevent 95 its ascension in a process of "take off", these propellers 29 may be caused to rotate at the proper velocity to bring about an increase of slight efficiency, which by coaction with the sustaining properties of the lighter than air bodies 2 and 3 and the lateral sustaining planes 8 will insure ascension of the equipped air ship. 100

By varying or selectively operating the propellers 18 mounted upon the opposite sides of the air ship body 9, it will be understood that the air ship may be more or less selectively navigated through its course. As a further means for controlling navigation of the air ship in a predetermined course and also for controlling ascension and descension, the usual rudders 31 and elevator planes 32 are provided adjacent the rearward end of the airship body 9, suitable controls being extended from these elements 31 and 32 (not shown herein) into the navigator's compartment 17 of the air ship or elsewhere such as conditions or preference may dictate. 110 115

Manifestly, the construction shown is capable of considerable modification and such modification as is within the scope of my claims, I consider within the spirit of my invention. 125

I claim:

1. An air ship of the character described 130

comprising a super structure, lighter than air sustaining bodies formed within said super structure, a pair of lateral oppositely disposed sustaining planes secured to said

- 5 super structure below said lighter than air sustaining bodies and disposed longitudinally thereof and in parallelism to the same, a body supported from said super-structure, said body being divided into a plurality of 10 cargo receiving compartments, fuel tank receiving compartments provided in the lower portion of said body whereby to lower the center of gravity of the air ship, landing gear connected to the bottom of said body immediately 15 below said fuel tank receiving compartments, propeller means mounted outwardly and laterally of said body and rearwardly of the same, and other propeller means supported in normally horizontal 20 planes above said super structure and adapted to accelerate and effect ascension of the air ship.

2. An air ship of the character described comprising a super structure, lighter than air sustaining bodies formed in and carried by said super structure, a body secured to and arranged below said super structure, a plurality of oppositely disposed laterally extending sustaining planes fixed to the lower portion of said super structure below said lighter than air sustaining body and arranged in parallelism to said last mentioned bodies, propeller means mounted outwardly and laterally of said body and below said sustaining planes, means within the body for transmitting driving motion to said propellers, a plurality of longitudinally disposed vertically extending tubes supported in and passing through said body and super structure, annular collars carried upon the upper ends of said tubular bodies above the super structure, normally horizontally positioned propeller means rotatably mounted in said annular collars and connected to said first mentioned propeller driving means, said body

being divided into a plurality of decks, one of said decks having a multiplicity of compartments thereupon and the other of said decks having fuel tank receiving compartments therein adapted with the placement 50 of fuel tanks in the same to lower the center of gravity of the air ship, and landing gear secured to the bottom of said body and immediately below said fuel tank receiving compartments. 55

3. In an airship, a horizontal longitudinally extending plane, a pair of tubular lighter than air sustaining bodies mounted longitudinally on the intermediate portion of the plane, a semi-circular roof covering the said sustaining bodies, and a fuselage secured to and suspended from the intermediate portion of the plane and extending in a longitudinal position thereunder, the sides of the plane projecting laterally beyond the sides of the 60 roof and fuselage to provide longitudinal stabilizing wings. 65

4. In an airship, a horizontal longitudinally elongated plane, a plurality of lighter than air sustaining tubes disposed longitudinally on the intermediate portion of the plane, a fuselage depending from the intermediate portion of the plane and arranged longitudinally thereunder, the longitudinal side portions of the plane being arranged to 70 project outwardly of the sustaining body and fuselage to provide stabilizing wings, a landing gear connected to the bottom of the fuselage, a plurality of vertically disposed tubes arranged through the fuselage, plane 75 and sustaining tubes, elevating propellers operatively mounted in the upper open ends of the vertical tubes, a plurality of driving propellers mounted outwardly and laterally of said body arranged in a horizontal plane, and 80 means for driving the said propellers. 85

In witness whereof I have hereunto set my hand.

JOSEPH E. PIGEON.
